UNITED STATES PATENT OFFICE.

JOSEPH G. REDDICK, OF PORTLAND, OREGON.

NON-REFILLABLE BOTTLE.

1,072,497.

Specification of Letters Patent.

Patented Sept. 9, 1913.

Application filed September 8, 1910. Serial No. 581,113.

To all whom it may concern:

Be it known that I, JOSEPH G. REDDICK, a citizen of the United States, residing at Portland, in the county of Multnomah and 5 State of Oregon, have invented a new and useful Non-Refillable Bottle, of which the following is a specification.

The invention relates to improvements in non-refillable bottles, and the application 10 is filed to take the place of an application filed July 31, 1906, Serial No. 328,602, of a similar device.

The object of the present invention is to improve the construction of non-refillable 15 bottles, and to provide a simple, inexpensive and efficient valve mechanism, constructed of material, which will not affect the contents of the receptacle, and adapted to be readily applied to the neck of a bottle or 20 analogous receptacle after the same has received its original contents, and capable of effectually preventing the introduction of a liquid into it, whereby fraudulent adulteration of the contents of the bottle and the 25 filling of the same are avoided.

With these and other objects in view, the invention consists in the construction and novel combination of parts hereinafter fully described, illustrated in the accompanying 30 drawing, and pointed out in the claims here- to appended; it being understood that various changes in the form, proportion, size and minor details of construction, within the 35 scope of the claims, may be resorted to without departing from the spirit or sacrificing any of the advantages of the invention.

In the drawing: Figure 1 is a vertical sectional view of a non-refillable bottle, constructed in accordance with this invention. 40 Fig. 2 is a horizontal sectional view on the line 2—2 of Fig. 1. Fig. 3 is a similar view on the line 3—3 of Fig. 1. Figs. 4 and 5 are detail perspective views of the sections of the valve casing.

45 Like numerals of reference designate corresponding parts in all the figures of the drawing.

In the embodiment of the invention illustrated in the accompanying drawing, the 50 valve mechanism comprises in its construc-

tion a cylindrical valve casing split longitudinally for a portion of its length to form semi-cylindrical sections 1 and 2, which when fitted together are interlocked by the means hereinafter described, and are retained in 55 their interlocked relation when introduced into the neck 3 of a bottle 4 or analogous receptacle. The sections of the valve casing are designed to be constructed of glass or other suitable material, which will not affect 60 the contents of a receptacle, and the section 1 is provided at the top with an integral horizontal top wall 5, which extends over and against the upper end of the other semi- cylindrical section 2. The semi-cylindrical 65 section 2 is provided at its lower end with an integral tubular portion 6, having a valve seat 7 and provided with a semi-circular peripheral recess 8, extending around one side of the valve seat and receiving the lower 70 end of the semi-cylindrical section 1, which is provided at opposite sides of its lower end with horizontal projecting lugs 9, fitting in corresponding recesses 10 of the section 2, whereby the two sections are interlocked and 75 held against longitudinal movement on each other. The recesses 10 are located at opposite sides of the semi-cylindrical section 2, and when the valve casing is placed in the neck of the bottle, the sections are positively retained in their interlocked relation. 80

The lower end of the tubular portion is provided with an annular peripheral recess 11, for the reception of an elastic packing ring or gasket 12, constructed of cork, or 85 other suitable material and arranged to engage the neck of the bottle to provide a tight fit for the valve casing and to prevent any of the liquid contents of the bottle from flowing between the valve casing and the 90 neck, should there be any space due to any irregularity in the form of the neck. The lower tubular portion of the section 2 is also provided at an intermediate point between its upper and lower ends with an annular 95 groove 13, and it has a semi-spherical concavity 14 in the bottom of the groove to receive a locking ball 15 of any suitable material. The ball when arranged in the concavity or recess 14 does not, as illustrated 100

in dotted lines in Fig. 1 of the drawing, project beyond the contour of the valve casing and the latter may, when the ball is in such position, be introduced into the neck of the bottle. The neck of the bottle is provided with an interiorly arranged annular groove 16, and when the groove of the valve casing registers with the groove in the neck of the bottle, the locking ball 15 will drop out of the recess and lock the valve casing within the neck 3. When the locking ball 15 leaves the recess, it is arranged partially within each of the grooves 13 and 16 and effectually prevents the valve casing from moving either up or down. When the bottle is turned, the ball will roll around the channel or run-way formed by the grooves 13 and 16 and will pass the recess without entering the same. When the bottle is made of opaque, semi-opaque, or glass, the locking mechanism will be concealed and it will be practically impossible to sink the locking ball in the recess 14.

The valve casing is provided at its upper end with an annular series of peripheral outlet openings 17, formed by notches or recesses in the top 5 and in the upper ends of the walls of the cylindrical casing. The walls of the casing are of a thickness equal to the depth of the recesses in the top 5 to prevent an instrument from being introduced into the openings for affecting the operation of a valve 18. The valve casing is also provided at the inner faces of its walls with an annular series of longitudinal guide ribs 19, extending upwardly from the valve seat and coinciding with the outlet openings 17 and increasing the thickness of the walls at such points and projecting inwardly a sufficient distance to effectually prevent an instrument reaching the valve 18. The longitudinal ribs are spaced at their upper ends from the top wall 5, and they provide intervening grooves or passages to permit the liquid to flow out of the bottle and the air to enter the same, so that the contents of the bottle may be freely decanted. The longitudinal ribs of the sections 2 terminate short of the lower edge of such section and are seated upon the raised valve seat 7, the lower edge of the said section 2 being arranged in the said peripheral recess 8.

The valve 18 is floatable and is constructed of cork, or other suitable material sufficiently light to float, but it can be constructed of glass and made hollow to render it buoyant. The valve consists of a cylindrical upper portion and a rounded semi-spherical lower portion, which is adapted to seat itself within the upper end of the tubular portion 6 of the valve casing. The upper cylindrical portion of the valve is provided with an annular recess 20, forming an upper guiding flange 21 and a lower guiding edge 22, which are of a diameter to fit snugly within the annular series of the longitudinal

ribs 19 and be guided by the same. The recessing of the cylindrical portion reduces the friction and enables the valve to seat itself more readily. The valve is held in its seat by a ball-shaped weight 23, constructed of glass or any other suitable material and arranged to rest upon the upper end of the valve when the bottle is in an upright position. The ball-shaped weight assists in reseating the valve, and is adapted to roll freely in the space between the latter and the upper end of the valve casing, and it rolls outwardly from the valve when the bottle is inverted below a horizontal position to permit the liquid contained within the bottle to be poured out. The floatable valve is readily moved outward by the liquid, and it is as readily moved inward by exterior pressure resulting from an attempt to introduce a liquid into the bottle. The pressure of such liquid not only acts against the outer or upper end of the cylindrical portion of the valve, but the recessing of the cylindrical portion forms an inner or lower shoulder at the edge 22 for the liquid to act against in seating the floatable valve. When the valve is open, the liquid is adapted to pass freely around the same to the outlet openings 17.

Having thus fully described my invention, what I claim as new, and desire to secure by Letters Patent, is:

1. A device of the class described including a valve casing having a valve seat at the lower portion and provided with a closed top wall, and having an annular series of outlet openings at the top and formed by registering recesses in the periphery of the top wall and the side wall of the casing, said valve casing being also provided with an annular series of vertical guiding ribs extending from the valve seat and spaced at the top from the underside of the top wall, said ribs coinciding at their upper ends with and terminating at the bottoms of the said recesses of the side wall and projecting inwardly from the recesses to form guards thereat, and a valve fitting snugly within and guided by the annular series of longitudinal ribs and co-acting with the valve seat.

2. A device of the class described including a cylindrical valve casing having a valve seat at the lower portion and composed of two semi-cylindrical sections having interlocking portions, one of the sections being provided with an integral top wall closing the upper end of the valve casing, said valve casing having an annular series of recesses at the periphery of the top wall, and the side wall of the casing having registering recesses and provided on its inner face with an annular series of vertical guiding ribs extending from the valve seat and spaced at the top from one side of the top wall, said ribs coinciding at their upper

ends with and terminating at the bottoms of the recesses of the side wall and projecting inwardly from the said recesses to form guards thereat, and a valve fitting snugly within and guided by the annular series of longitudinal ribs and co-acting with the valve seat.

In testimony that I claim the foregoing as my own I have hereto affixed my signature in the presence of two witnesses.

JOSEPH G. REDDICK.
